UNITED STATES PATENT OFFICE.

ALBERT H. SISSON, OF HIGH POINT, NORTH CAROLINA, ASSIGNOR TO FORSYTH BROTHERS COMPANY, OF CHICAGO, ILLINOIS, A CORPORATION OF ILLINOIS.

SASH CONSTRUCTION.

1,089,873.

Specification of Letters Patent. Patented Mar. 10, 1914.

Application filed September 22, 1913. Serial No. 791,040.

To all whom it may concern:

Be it known that I, ALBERT H. SISSON, a citizen of the United States, residing at High Point, in the county of Guilford and 5 State of North Carolina, have invented certain new and useful Improvements in Sash Construction, of which the following is a specification.

This invention while relating to sash construction in general has for its particular object the formation of the sash corner, lock and lock plate, of such shape and in such relation that they coöperate in effecting a compact rigid construction of which the sash 10 members may be much narrower than is ordinarily found to be necessary to accommodate the lock and of lighter material due to the reinforcing action of the lock plate. The lock plate also serves as a housing for 15 the locking elements and has formed integral therewith the sash lift. Moreover, the engagement of the lock with the window operates to normally thrust the sash therefrom and maintain the same under spring 20 tension against the opposite guide to prevent rattling and more effectively exclude the elements.

Other advantages from the standpoint of mechanical construction and operation will 25 be apparent to those skilled in this art.

In order that the invention may be readily understood two practical embodiments of the same are set forth in the accompanying drawings and in the description based 30 thereon. As the invention is also capable of embodiment in other and varied constructional forms the drawings and description are to be construed as illustrative and not in an unnecessarily limiting sense.

40 In the drawings: Figure 1 is a front elevation of one form of sash corner shown in assembled relation to the window frame which is partially broken away; Fig. 2 is a horizontal section taken on the line 2—2 of 45 Fig. 1; Fig. 3 is a vertical section on the line 3—3 of Fig. 2; Fig. 4 is a vertical section on the line 4—4 of Fig. 2; Fig. 5 is a view similar to Fig. 1 showing another form of construction; Fig. 6 is a vertical section through the sash looking toward the 50 lock; Fig. 7 is a horizontal section on the line 7—7 of Fig. 5; and Fig. 8 is a vertical section on the line 8—8 of Fig. 5.

Having reference particularly to Figs. 1 55 to 4 inclusive the sash members, that is to

say the rail 11 and stile 12 are shown as mitered at 13 and connected to form a sash corner. The sash members 11 and 12 are here shown as formed of sheet metal tubular in cross section having a reentrant portion 60 14 forming a groove for the reception of glass 15 with suitable interposed packing 16. It is desirable both from the standpoint of economy of material and also to encroach as little as possible upon the window opening that the rail and stile be as narrow as is consistent with strength, and with the necessity of affording a proper support and bearing for the sash lock. Ordinarily the sash members are made wider than would 65 be otherwise necessary for the reason that one, and usually the rail, must be made wide enough to accommodate the lock plate and lock. By the present invention I am enabled to reduce the width of the rail and stile to 70 an inch or less and also to employ lighter material for the same.

In carrying out the invention I provide a lock plate 17 which is secured to the rail and stile, advantageously by screws 18 extending through into an interior corner reinforcement hereafter described. The lock plate is angular in outline and preferably L-shaped, one leg extending longitudinally of each of the sash members for a considerable 85 distance beyond the corner of the sash thus bridging the mitered joint between the members. The inner edges of the plate are deflected laterally toward the glass as indicated at 19 and fit snugly against the inner 90 edges of both the rail and stile. The horizontal leg of the plate also preferably extends upwardly and inwardly beyond the rail as indicated at 20 and constitutes a housing for the bolt 21 of the lock, the 95 finger piece 22 of which projects through the plate extension 20. The inner edge of the extension 20 is substantially vertical and in line with the outer wall of the glazing groove so as to lie closely adjacent the 100 outer face of the glass while the sash lift 23, formed integral with the plate, projects outwardly in a substantially horizontal direction. It will be observed that the outer edges of the lock plate 17 do not extend to 105 the outer edges of the rail and stile but are sufficiently remote therefrom to clear the stop 24 and the sill 25 thus presenting for engagement with the stop and sill a plane surface throughout and not requiring the 110

lock plate to be inset in the sash. The locking bolt 21 is provided with an angular portion 26 terminating in a hook 27 adapted to engage below or above projections 28, 29 of the metallic strip 30 secured on the inner face of the stop 24. The hook 27 is pressed outwardly into engagement with the strip 30 by means of a torsional spring which surrounds the bolt 21 within the housing of the plate, this form of bolt actuating spring being old and well known and for that reason not illustrated. The tension of the spring is sufficient to press the end of the latch 26 strongly against the plate 30 and thus force the sash in the opposite direction against the stop 24 to prevent rattling and more effectively exclude air, dust and moisture.

The snug fit of the deflected portions 19 of the lock plate over the inner edges of the sash members, as also the snug fit of the bolt 21 within the recess 32 of the stile of themselves tend to effect a firm engagement of the parts, thus materially assisting and relieving the screws 18 from undue strain. This result is further enhanced by the provision of a stud 33 projecting forwardly from the lock plate into engagement with an aperture in the face of the stile.

Having reference to the form of construction shown in Figs. 5 to 8 inclusive, here the rail 41 and the stile 42 are likewise connected by mitered joint 43 and the lock plate 44 is also of L construction and extends for a considerable distance horizontally and vertically from the joint along the sash members. Both legs of the plate are similarly deflected inwardly, as shown at 45, to fit snugly over the inner edges of the stile 40 and rail and as an additional point of support a portion 46 of the plate is bent inwardly as a stud beyond the edge of the portion 45 of the plate 44 into engagement with a recess of the stile to constitute in effect a stud engaging within the recess as an aperture while the plate as a whole is secured to the sash members by means of the screws 47, 47 passing through the plate into threaded engagement with an interior reinforcing lining referred to in connection with Figs. 1 to 4 inclusive and also by means of screws 49, 49 which have threaded engagement with the threaded interior of the screw headed sleeves 50. The lock plate 44 has formed in 55 tegular therewith, as in the former case, a sash lift 51 which, however, in the present instance instead of being formed upon the horizontal leg of the plate is formed upon the vertical leg thereof. In this form of construction the lock instead of being mounted within the lock plate is pivoted upon a screw 52 in the stile of the sash and comprises a finger piece 53 projecting adjacent the lift 51 and also a angular extension 54 terminating in a hook nose 55 which

is adapted to engage within a recess 56 of the frame 57 and to bear under tension of the spring 58 upon the inner wall of said recess so as to force the sash in the opposite direction and prevent rattling. In order to safe-guard the pivot screw 52 against turning a pin 59 is seated within the plate 44 and projects inwardly therefrom into engagement with the slot of the screw. In this form of construction the lower edge of the rail 41 is shown as provided with a re-entrant dove-tail groove 60 adapted to receive a correspondingly shaped slide 61 having seated therein a rubber strip 62 which bears upon the window sill 63 to prevent the entrance of the elements underneath the sash.

In order to provide a particularly rigid and efficient connection between the rail and stile at each corner of the sash a reinforcing lining 64 is provided which is L-shaped in side elevation and substantially U-shaped in cross section, the U opening inwardly. The limbs of the U are curved inwardly at their extremities, as indicated at 65, so as to follow the inward curvature of the sash members into the restricted space at each side of the glazing groove and terminate with their edges abutting against the walls of said groove as clearly shown in the drawing. Heretofore it has not been usual to have the reinforcement extend into this space on each side of the glazing groove and the lateral strength of the reinforcement has been correspondingly limited.

As shown in Fig. 1, the recess 32 of the stile within which is accommodated the locking bolt 21 and its angular portion 26, also extends through the reinforcing lining 64, but by reason of the turned edge 65 of the latter the slot does not extend entirely to the edge and the weakening effect of the slot upon the stile is therefore much reduced.

That portion of the reinforcement 64 which extends into the lower rail is slotted as indicated in Fig. 6, so as to embrace the dove-tail groove 60 and the slide 61, the relative position of the two walls of the reinforcement being maintained by a spacing bolt 66 extending transversely and rigidly joining the two walls.

Not only does the reinforcing lining 64 stiffen the side and edge walls of the rails and stiles, but by reason of its extending into the space on each side of the glazing groove and also embracing the dove-tail groove within which the backing strip 62 is mounted it serves to stiffen the angular connections of the frame and assist in maintaining the proper relation between the parts.

In both forms of construction shown it will be observed that the lock plate does not extend the full width of the sash members and that it extends inwardly around the

inner edge of the sash members, snugly fitting the same, and that the sash lift is formed integral with such plate within the area bounded by the sash, thus providing for the mounting of both the stationary and movable locking members in front of the glass and within the sash so that very narrow sash members may be used which are rigidly reinforced by means of the plate extending along both members and bridging the joint, and also by the firm bearing of the screws in the reinforcing lining and the stiffening of the sash members at the corners by said reinforcement.

15 I claim:

1. In sash construction, the combination with a rail and stile connected to form a sash corner, of an exterior plate secured to both of the sash members and bridging the joint therebetween, the inner edges of the plate deflected laterally to form a flange fitting over the inner edges of the members, and a lock operating member carried by the plate and extending into the glass area of the sash, substantially as described.

2. In sash construction, the combination with a rail and stile connected to form a sash corner, of an exterior L-plate secured to both of the sash members and bridging the joint therebetween and extending from the corner along each of said members, the inner edges of the plate deflected laterally to form a flange fitting over the inner edges of the members, and a lock operating member carried by the plate and extending into the glass area of the sash, substantially as described.

3. In sash construction, the combination with a rail and stile connected to form a sash corner, of an L-plate secured to both of the sash members and bridging the joint therebetween and extending from the corner along each of said members, the inner edges of the plate deflected laterally to form a flange fitting over the inner edges of the members, a lock operating member mounted on the plate, and a stud integral with the plate and engaging within a recess of the sash, substantially as described.

50 4. In sash construction, the combination with a rail and stile connected to form a sash corner, of a plate secured to both of the sash members and bridging the joint therebetween and extending from the corner along each of said members, the inner edges of the plate deflected laterally to form a flange fitting over the inner edges of the members, a sash lift formed integral with the plate, and a lock covered by the plate and having a finger piece disposed adjacent the lift, substantially as described.

55 5. In sash construction, the combination with a rail and stile connected to form a sash corner, of an L-plate overlying the joint and extending from the corner along

the side face of each of said members, said plate projecting inwardly beyond the inner edges of the sash members into the space bounded by said members, a lift carried by the plate, a lock covered by the plate, and a finger piece disposed adjacent the lift, the lift and finger piece being entirely within the area bounded by the inner edges of the sash members, substantially as described.

6. In sash construction, the combination with a rail and stile connected to form a sash corner, of an L-plate overlying the joint and extending from the corner along the side face of each of said members, the plate projecting inwardly beyond the inner edges of the sash members and overlying said inner edges in snug fitting engagement, a lift formed integral with the inner extension of the plate, a lock covered by the plate, and a finger piece disposed adjacent the lift, the lift and finger piece being entirely within the area bounded by the inner edges of the sash members, substantially as described.

7. In sash construction, the combination with a narrow rail and stile connected to form a mitered sash corner, of an L-plate secured upon the face of both the sash members and bridging the mitered joint therebetween and extending from the corner along each of said members, the outer edges of the plate disposed at a distance from the outer edges of the sash members, and the inner edges of the plate deflected laterally to form a flange fitting over the inner edges of the sash members, a lift carried by the plate, a lock covered by the plate and having a finger piece arranged adjacent the lift, the lift and finger piece arranged within the area bounded by the inner edges of the sash, substantially as described.

8. In sheet metal sash construction, the combination with a rail and stile connected to form a sash corner and provided along their inner edges with a groove, of an interior reinforcement comprising a lining U-shaped in cross section with the limbs extending into the space on each side of the groove, of a plate secured to both of the sash members and bridging the joint therebetween, means passing through the sash members and connecting the plate and reinforcement, and a sash lift carried by the plate, substantially as described.

9. In sheet metal sash construction, the combination with a rail and stile connected to form a sash corner with their inner edges curved and provided along a medial line with a glazing groove, of an interior corner reinforcement secured to adjacent sash members and comprising a lining U-shaped in cross section with the limbs deflected inwardly and extending into the closed space on each side of the groove and abutting the walls of the groove, an L-plate secured to both of the sash members and bridging the

- 4
- joint therebetween and extending beyond the corner along each of said members, the inner edges of the plate deflected laterally to form a flange fitting over the curved inner edges of the sash members, a lock member formed integral with the plate, and fastening means extending through the sash members and connecting the plate and interior reinforcement, substantially as described.
- 10 10. In sheet metal sash construction, the combination with a rail and stile connected to form a sash corner and provided along their inner edges with a groove, of an interior reinforcement comprising a lining extending into the closed space on each side of the groove, and a spacing member spanning the space between the side walls of the sash, substantially as described.
- 11 11. In sheet metal sash construction, the combination with a rail and stile connected to form a sash corner and provided along their inner edges with a groove, of an interior angular reinforcement U-shaped in cross section with the limbs extending into the space on each side of the groove, and a spacing member spanning the space between the limbs of the reinforcement, substantially as described.
- 12 12. In sash construction, the combination with sash members connected to form a sash corner, of a lock carried by said members, and a reinforcement, the reinforcement comprising an interior lining having a portion spaced from the side wall of the sash member, and a lock plunger mounted for movement within the space between the reinforcement and sash wall, substantially as described.
- 13 13. In sash construction, the combination with sash members connected to form a sash corner, of a lock carried by said members, and a reinforcement, the reinforcement comprising an interior lining having a portion spaced from the side wall of the sash member, a pivot spanning the space between the reinforcement and sash wall, and a lock plunger mounted on said pivot, substantially as described.
- In testimony whereof I have hereunto signed my name in the presence of two subscribing witnesses.
